UNITED STATES PATENT OFFICE.

FRANK M. PIERCE, OF CHICAGO, ILLINOIS.

HORIZONTAL-SHUTTLE WRAPPING-MACHINE.

1,399,989.

Specification of Letters Patent. Patented Dec. 13, 1921.

Application filed November 13, 1920. Serial No. 423,791.

To all whom it may concern:

Be it known that I, FRANK M. PIERCE, a citizen of the United States, and a resident of the city of Chicago, in the county of Cook and State of Illinois, have invented certain new and useful Improvements in a Horizontal-Shuttle Wrapping-Machine; and I do hereby declare that the following is a full, clear, and exact description of the same, reference being had to the accompanying drawings, and to the numerals of reference marked thereon, which form a part of this specification.

This invention relates to an improved wrapping machine and particularly to a machine which is adapted to spirally apply a protecting wrapping on annular objects of various sizes.

It is often desirable that means be provided for protecting annular objects, such as automobile tire casings, rolls of wire, etc., during the time intervening between their manufacture and use; and said protecting means usually comprises a spiral wrapping 25 of paper or other suitable material which is applied with a wrapping machine.

The majority of practical wrapping machines accomplish this effect by rotating the article to be wrapped through the eye of a 30 rotatable wrapping material shuttle, the relative rotation of the article and the shuttle causing the wrapping material on the shuttle to be spirally applied on the article.

In order to wrap articles of various sizes 35 it is necessary to have adjustable means whereby the same are supported in the machine, and in order that the wrapping may be effectively accomplished it is desirable that said adjustable supporting means be 40 arranged to properly position various sizes of articles with reference to the shuttle. It is, of course, also desirable that the wrapping machine be of simple and strong construction and that the controls therefor 45 adapt the same to be operated at high speed.

It is an object of this invention to provide a wrapping machine having a horizontally mounted wrapping material carrying shuttle and having adjustable means for rotatably supporting articles to be wrapped in 50 a vertical position.

It is another object of this invention to provide a wrapping machine having an open gap, horizontal wrapping material carrying shuttle, and having differentially ad-

justable means for rotatably supporting an article to be wrapped in a vertical position.

It is a further object of this invention to provide a wrapping machine wherein supporting means for an article to be wrapped are adjustable toward and away from a wrapping mechanism in an angular direction.

It is an important object of this invention to provide a wrapping machine adapted to wrap annular articles of various sizes and having adjustable means adapted to support said articles in the proper position for wrapping.

Other and further important objects of this invention will be apparent from the disclosures in the specification and the accompanying drawings.

The invention (in a preferred form) is shown on the drawings and hereinafter more fully described.

On the drawings:

Figure 1 is a side elevation of a wrapping machine embodying the principles of this invention.

Fig. 2 is an end elevation of the same.

Fig. 3 is a top plan view of the wrapping machine.

Fig. 4 is a section on the line 4—4 of Fig. 3.

Fig. 5 is a section on the line 5—5 of Fig. 1.

Fig. 6 is a fragmentary section on the line 6—6 of Fig. 1.

Fig. 7 is an enlarged top plan view of the wrapping material carrying shuttle.

Fig. 8 is a view of the supporting means on the line 8—8 of Fig. 1.

Fig. 9 is a detail view showing the guide for the supporting means.

As shown on the drawings:

The wrapping machine of this invention is supported upon a base 1 which is provided at its corners with legs 2 and which has upwardly extending open end frames 3 and 4 secured at its ends. Secured on the upper ends of said frames 3 and 4 and supported thereby is a bifurcated shuttle frame 5 which is shown in detail in Fig. 5 and which will be more specifically described hereinafter. Power for driving the various mechanisms of the wrapping machine is obtained from a shaft 6 which is journaled in a bearing 7 on the base of the frame 1 as clearly shown in Fig. 6. Mounted on said

110

shaft 6 is a grooved driving pulley 8 and power from an outside source such as an electric motor is transmitted to said shaft through a gear 9 and a friction clutch 10 which are of the usual construction and which are clearly shown in Fig. 1. Said friction clutch 10 and gear 9 are mounted on the outer end of the shaft 6 which extends outwardly from the frame 1 and has its outer 10 end journaled in a bearing 11 which is supported on an auxiliary frame 12. The friction clutch 10 is adapted to be engaged and disengaged by means of a lever 13 and in order to quickly stop the rotation of the shaft 15 6 and the operation of the machine when said clutch is disengaged a brake 14 is mounted on the shaft 6 adjacent the bearing 11 and is adapted to be set by the lever 13 when the same is actuated to disengage the clutch 10. Suitable means are provided for moving said 20 lever 13 back into neutral position so that the brake 14 is again released after the machine is stopped. Rotatable wrapping material carrying means are mounted in a grooved 25 guide-way 15 secured to the upper side of the frame 5, and said means ordinarily comprise an open gap horizontal shuttle 16 which has a downwardly extending flange 17 adapted to be engaged in said guide-way. Said shuttle 30 is also provided with a peripheral groove 18 which is adapted to receive a driving means.

Mounted on the upper face of said shuttle 16 is a reel 19 which is adapted to receive a spool of wrapping material 20 and from said 35 spool 20 the wrapping material is led through an adjustable tension device 21 to an edge-folding device 22 which folds the upper edge thereof downwardly. From said edge-folding device the wrapping material is led 40 around an angle roller 23 which creases the fold in the upper edge of the wrapping material and guides the same to an object 24 such as a bundle of wire or an automobile tire casing which is positioned substantially centrally 45 of the shuttle in a gap 25 formed therein.

The drive for said shuttle comprises a belt or rope 26 which is engaged around the driving pulley 8 on the shaft 6 and which extends 50 upwardly over vertical pulleys 27 which are journaled in brackets 28 on the inside of the frame 3. From said vertical pulleys 27 said rope or belt 26 is trained around horizontal pulleys 29 which are journaled on shafts 30 55 extending upwardly from the outer extremities of the frame 5. After leaving said horizontal pulleys 29 the rope or belt 26 is engaged in the peripheral groove 18 in the shuttle 16 and upon leaving said groove is trained 60 around grooved horizontal pulleys 31, 32 and 33, which are journaled on shafts 34, 35 and 36, extending upwardly from the frame 5 as clearly shown in Fig. 3. Since said driving belt or rope 26 is of comparatively great 65 length relative to the length of the gap 25 in

the shuttle 16, the engagement thereof across the gap makes no appreciable difference in the rotation of the shuttle.

In order that said shuttle 16 may be conveniently rotated to position the same for the insertion or removal of an annular article, a suitable hand wheel 37 is mounted on one of the shafts 30 and may be rotated to rotate the pulley 29 on said shaft and thus rotate the shuttle 16 to position the same as desired.

The mechanisms which are employed for adjustably and rotatably supporting the article to be wrapped will now be described. The outer portions of the frame 4 extend diagonally downwardly and outwardly and in each of said outer portions is formed an angular slot 38, the upper end 39 of which extends in a vertical direction for a short distance. Formed on the inner sides of the outer portions of the flange 4 and in continuation of the slot 48 are angular grooves 40 and vertical extensions 41 of said angular groove 40 are parallel with the vertical slot extension 39 of the slot 38. A detail of the 90 construction of said slots and grooves is clearly shown in Fig. 9. Rollers 42 and 43 which are journaled on shafts 44 and 45 of a frame 46 are engaged respectively in said slots 38 and grooves 40, and thus act to adjustably support said frame 46 therein. Mounted on shafts 47 and 48 extending transversely of said frame 46 are grooved supporting rollers 49 and 50 which act to support the annular article which is to be 100 wrapped in a vertical position and to rotate the same through the gap 25 in the shuttle 16. 95

The mechanism whereby said frame 46 and the supporting rollers 49 and 50 are raised and lowered in the slots 38 and 39 will now 105 be described. Extending outwardly from each side of the frame 46 near the lower portion thereof is a short shaft 51 and mounted on each of said shafts is a sprocket wheel 52 and a flanged roller 53 which is 110 adapted to be engaged over and travel on ribs 54 on the inner sides of the supporting members of the frame 4. Secured to each side of the frame 4 and on the outside thereof at point 55 is one end of a sprocket chain 56. 115 Said sprocket chains are led downwardly around the sprocket wheel 52 and upwardly around sprocket wheels 57 which are rotatably mounted on the outside of the frame 4 above the point 55. These sprocket chains 120 extend longitudinally of the outside of the machine and the ends thereof are each connected to a drum 58 mounted on a shaft 59 which is journaled in brackets 60 supported on the frame 3. Means are provided 125 for rotating said shaft 59 whereby the sprocket chains 56 may be shortened or lengthened by winding the same on the drums 58 or unwinding them therefrom. For this purpose a worm gear 61 is secured 130

on the said shaft 59 outside of one of the drums 58 and is adapted to be engaged by a worm 62 which is mounted on a vertical shaft 63 pivoted in one of the brackets 60 and provided at its upper end with a crank 64 whereby it may be rotated. The rotation of said crank 64 serves to wind the chain 56 on the drums 58 or to unwind them therefrom whereby the supporting rollers 49 and 50 are moved toward or away from the shuttle 16; and since the direction of movement of said rollers is guided by the engagement of the rollers 44 in the slots 38 and 39, said rollers will be at all times positioned so that 15 the object 24 which is to be wrapped will pass substantially through the center of the shuttle. Since this angular movement of the rollers 49 and 50 on the frame 46 is not practicable for annular objects of small diameters, the vertical portion 39 of the slot provides for a direct up and down adjustment for these sizes. In order to allow an extreme upward movement of the frame 46 the slots 65 are provided in the under side of the 20 frame member 4 to allow the shaft 51 on said frame 46 to move therein.

The mechanism which is provided for rotating the supporting rollers 49 and 50 at different rates of speed and simultaneously 30 with the rotation of the shuttle 16 will now be described. Power for driving said mechanism is obtained from a worm 66 which is mounted on the shaft 6 and which meshes with a worm gear 67 secured to a shaft 68 which is journaled transversely of a frame 69 mounted on the base 1 inside the frame 3. Mounted on said shaft 68 is a gear 70 and power from said shaft is transmitted to said gear 70 and through a suitable sliding 40 selective gear mechanism 71, 72, 73, to a shaft 74 which is also journaled transversely of the frame 69 and which has secured on one end thereof a sprocket wheel 75 as clearly shown in Figs. 4 and 6. Rotatably mounted 45 on the frame 69 adjacent the sprocket wheel 75 is an idler sprocket wheel 76 and engaged around said sprocket wheel 75 and over said idler sprocket wheel 76 is a driving sprocket chain 77 which is engaged over sprocket 50 wheels 78 and 79 mounted on the shafts 47 and 48 outside the frame 46 as clearly shown in Figs. 1 and 2. Said chain 77 extends downwardly from the sprocket wheel 79 over an idler sprocket wheel 80 which is 55 mounted on the shaft 51 near the lower part of the frame 46.

Means for maintaining a proper tension on the driving chain 77 at all times, comprise a weighted arm 81 which is pivotally 60 mounted on the end of the shaft 74 and which has pivoted thereon an idler sprocket wheel 82 which is adapted to engage said driving chain 77 between the idler sprockets 76 and 80. As a result of this construction 65 the weight of said arm 81 will always be

imposed upon the lower loop of the driving chain 77 and the slack in said driving chain will be automatically taken up for all positions of the supporting rollers 49 and 50.

In order that the upper portion of the annular object which is being wrapped may be accurately guided a pair of angularly mounted rotatable guiding rollers 83 are provided. Said guiding rollers 83 are best shown in Fig. 2 and are adjustably supported on a vertical portion 84 which extends upwardly from the outer end of the frame 5, by means of a clamp bracket 85 on said portion and an arm 86 pivotally mounted on said clamp bracket. 70 75 80

A mechanism 87 whereby a peripheral adhesive strip may be applied on the outside of the wrapping is supported from the frame 5 on an upwardly extending column 88 thereon and a cutter 89 on said mechanism 87 provides means whereby said peripheral strip may be severed after the object in the machine is wrapped. 85

The operation is as follows:

The annular article 24 which is to be wrapped is placed on the supporting rollers 49 and 50 and the crank 64 is rotated to raise or lower said supporting rollers to properly position said article with reference to the shuttle 16. For best results in wrapping it is desirable that the article pass substantially through the center of said shuttle and the provision of the angular guiding means for said supporting rollers makes this possible. On account of the convenient adjustment of said supporting rollers it is also possible to bring the extreme inward point of the periphery of the annular article approximately on a line with the top of the roll of paper on the shuttle which is the most desirable position for wrapping and also to vary the position of this point slightly as the varying cross-sectional area of the article to be wrapped demands. This adjustment is made very easy by the fact that the operator can readily judge the position of this extreme inner point with relation to the shuttle by glancing at the same. After the supporting rollers 49 and 50 are properly adjusted the upper guiding rollers 83 are placed on the top of the article 24 and wrapping material from the spool 20 is engaged through the tension device 21, the edge-folder 22 and around the angle roller 23 and held against the article which is to be wrapped. The machine is then started by moving the lever 13 so as to engage the friction clutch 10 whereupon the driving mechanisms are rotated from the shaft 6 to effect the relative rotation of the article 24 and the shuttle 16, and to spirally apply wrapping material on the article. At the time the wrapping is begun the peripheral strip from the mechanism 87 is applied thereon, and when the wrapping is com- 115 120 125 130

pleted said peripheral strip is severed on the cutter 89. The amount of overlap of the wrapping may be varied by changing the speed of rotation of the rollers 49 and 50 through the change speed mechanism 70, 71, 72, 73. On account of the open gap 25 in the shuttle 16 articles to be wrapped and articles which have been wrapped are easily inserted therein and removed therefrom and manual rotation of the shuttle to properly position the same for this insertion or removal is conveniently effected by means of a hand wheel 37.

It will accordingly be observed that this invention provides a simple, effective wrapping machine which is adapted to be operated at high speed and in which the articles to be wrapped are supported in such a position that the wrapping thereof is effectively accomplished. That it is possible to obtain this result on various sizes of annular articles is directly due to the provision of the angular slots 38 whereby the supporting rollers 49 and 50 are differentially moved into adjusted position toward or away from the shuttle.

While there has been shown and described herein one type of shuttle and wrapping material applying mechanism, it is apparent that the wrapping machine of this invention could be successfully operated with various types of shuttles, for example, with a shuttle of the type wherein the wrapping material is contained in the interior thereof in folded layers.

It is understood that various details of construction may be varied through a wide range without departing from the principles of this invention and it is therefore not purposed to limit the patent granted otherwise than necessitated by the prior art.

Claims:

1. A wrapping machine comprising a frame, a rotatable shuttle thereon, means for rotatably supporting an article to be wrapped, and a slotted frame for guiding said supporting means, the upper portions of the slots in said frame being vertical and the lower portions thereof extending in an angular direction.

2. A wrapping machine comprising a frame, a rotatable shuttle thereon, means for supporting an article to be wrapped and rotating the same through the shuttle, a frame for said supporting means, and an angularly positioned track in which the frame is movable.

3. A wrapping machine comprising a frame, a rotatable horizontal shuttle thereon, adjustable means for rotatably supporting an article to be wrapped, and slotted guiding means for restraining movement of said supporting means to an angular direction relative to the shuttle.

4. A wrapping machine comprising a

frame, a rotatable shuttle thereon, adjustable means for rotatably supporting an article to be wrapped, and an angularly slotted frame for guiding said supporting means.

5. A wrapping machine comprising a frame, a rotatable horizontal shuttle thereon, adjustable means for rotatably supporting an article to be wrapped, a frame for said supporting means, an angularly slotted guiding means, and means on the second mentioned frame engaged in the slots in the driving means.

6. A wrapping machine comprising a frame, a rotatable shuttle thereon, means for supporting an article to be wrapped and rotating the same through the shuttle, a frame for said supporting means, an angularly positioned track in which the frame is movable, a sprocket on the second mentioned frame, a sprocket chain secured to the first mentioned frame and engaged under said sprocket, and means connected with said sprocket chain for moving the same to adjust the position of the second mentioned frame and the supporting means thereon.

7. A wrapping machine comprising a frame, a rotatable shuttle thereon, adjustable means for rotatably supporting an article to be wrapped, a chain drive for said means, and means for maintaining a substantially constant tension on said drive for all positions of the supporting means.

8. A wrapping machine comprising a frame, a rotatable shuttle thereon, adjustable means for rotatably supporting an article to be wrapped, a chain drive for said means, and gravity actuated means for maintaining a substantially constant tension on said drive for all positions of the supporting means.

9. A wrapping machine comprising a frame, a rotatable shuttle thereon, adjustable means for rotatably supporting an article to be wrapped, a flexible driving means for said adjustable means, and means for maintaining a substantially constant tension on said flexible driving means for all positions of the supporting means.

10. A wrapping machine comprising a frame, a rotatable shuttle thereon, means for supporting an article to be wrapped and rotating the same through the shuttle, and a guideway for said supporting means, the upper portions of said guideway being vertical and the lower portions thereof extending in an angular direction.

In testimony whereof I have hereunto subscribed my name in the presence of two subscribing witnesses.

FRANK M. PIERCE.
